The ornamental design for an optical fiber terminating apparatus, as shown and described.

Jul. 24, 2007 (JP) 2007-019977

DESCRIPTION

(51) **LOC (9) Cl.** **24-02**

FIG. 1 is a perspective view of an optical fiber terminating apparatus.

(52) **U.S. Cl.** **D24/133**

FIG. 2 is a front elevation view thereof. A rear elevation view is symmetrical with the front elevation view. A top plan view and a bottom plan view are identical with the front elevation view.

(58) **Field of Classification Search** D24/133,

FIG. 3 is a left side elevation view thereof.

D24/146, 147; 606/167, 170; 600/562, 564-567

FIG. 4 is a right side elevation view thereof.

See application file for complete search history.

FIG. 5 is an enlarged horizontal cross-sectional view of the central part of the front elevation view thereof; and,

(56) **References Cited**

FIG. 6 is a referential view showing use thereof, the optical fiber not forming a part of the claimed optical fiber terminating apparatus.
